UNITED STATES PATENT OFFICE

2,523,232

TRUSS

Moris Portnow, New York, N. Y.

Application November 4, 1946, Serial No. 707,616

3 Claims. (Cl. 128—95)

1

This invention relates broadly to trusses and more particularly to means whereby a truss may be worn with a much greater degree of comfort than is now possible.

There are broadly two types of trusses in common use. One type of truss comprises two springs each of which has a truss pad at one end. This truss is generally used in connection with double hernia. The other type of truss has one spring, having a truss pad at one of its ends. This type of truss is generally used in connection with single hernia. The present application relates more particularly to means associated with the double-hernia type of truss.

It is the principal object of the present invention to alleviate the pressure of the spring element of a truss against the body of the wearer, by providing a pad-like sheath for the spring element of a truss.

It is a further object of the present invention to provide a sheath for the spring element of a truss, the sheath being provided with a pad-like cap at one end, to ease the pressure of the free end of the spring against the body.

And yet another advantage of the present invention resides in the provision of a sheath for the spring element of a truss, the sheath having a cap formed at one end by dipping the end in a solution of moisture-proof material.

Still another purpose of the present invention resides in the provision of a sheath for the spring element of a truss, the sheath comprising a central tubular section for the spring, and two outwardly tapered edge sections, one for each side of the tubular section.

These and other meritorious objects and advantages, which will become more fully apparent as the description hereof proceeds, are attained by the novel construction and combination of parts, hereinafter described, and illustrated in the accompanying drawing, forming a material component of the present disclosure, and in which:

Figure 1 is a top plan view of a truss for double hernia, the truss having two springs, each of which is contained in a sheath of the present invention.

Figure 1a is a sectional view through one sheath and the spring contained therein, the section being taken on line 1a—1a of Figure 1.

Figure 2 is a front elevational view of the truss illustrated in Figure 1.

Figure 3 is a rear elevational view of the truss illustrated in Figure 1.

Figure 4 is a top plan view of a modified form

2

of truss, in which the rear ends of the springs are joined by an adjusting strap and the front ends of the truss are joined by an adjusting strap.

Figure 5 is a front elevational view of the left hand portion of the truss illustrated in Figure 4.

Referring in greater detail to the drawing, the truss illustrated in Figures 1 through 3 of the drawing is broadly referred to by the numeral 10. It comprises a pair of truss-pads 11 spacedly and 10 adjustably mounted on a brace 12, each end of the brace 12 being provided with a slot 13. In each of said slots 13 is movably retained a screw 14 each of said screws 14 being partly imbedded in the back of each truss pad 11. In this manner, 15 the relative distance between truss pads may be altered by moving each pad within the slot and retaining it in any adjusted position by tightening the screw in the conventional manner.

The truss further comprises two springs, 16 20 and 16a respectively, each of the springs adapted to be placed about and retained at one side of the waist of a wearer. Spring 16 is adapted to be retained in a sheath 15 and spring 16a is adapted to be retained in a sheath 15a in a manner 25 and for the purpose to be hereinafter described. Each of the sheaths had a pad-like cap superimposed at one of its ends, in a manner and for the purpose which will hereinafter be more fully explained, the caps being referred to by the numerals 17 and 17a respectively. Each of said caps may be provided with a stud 18 for selective engagement with any of the holes 20 in adjusting belt 19 to join the truss springs at the rear. Each 30 end of the brace 12 may be secured to the other end of springs 16—16a by means of rivets 21 or other retaining means. All of the elements referred to above, except sheaths 15—15a and caps 17—17a are old and well known in the truss art. They do not form part of the present invention 35 and are illustrated and described merely for explanatory purposes.

The present invention comprises sheaths 15—15a. Each of said sheaths is made from a tubular strip of rubber or other soft and flexible 45 material. Each sheath is slightly longer at one end than the spring which it is intended to contain, so that, when the spring is entered into the sheath it will stop just short of the sheath at the front where the truss pads are positioned. Each 50 of said sheaths comprises a central longitudinal section, 22—22a respectively in which springs 16 and 16a respectively are adapted to be retained, and the sheaths are further provided with two longitudinal edges, which extend throughout 55 the length of the central tubular section and

which are outwardly tapered as at 23—23a and 24—24a respectively. One end of each sheath is closed by having a pad-like cap 17 and 17a respectively superimposed thereon. This is done in the following manner, although other methods may be found to be preferable: One end of the sheath is inserted in a solution of liquid rubber of the kind commonly known by the trade name "Latex," although any other suitable and desirable solution may be used. In order to prevent the solution from getting into the tubular opening, the opening is sealed at its edge either by using a staple or by inserting a small piece of rubber into the end of the opening or in any other suitable and desirable manner. This, of course, must be done before the end of the sheath is inserted into the liquid rubber solution. After the solution on the sheath is dry, the cap, which has now formed, is dipped into a conventional binding compound and, after this is dry, it is again dipped into a solution of liquid rubber. After the second solution has become dry, the sheath is placed into an oven at a predetermined temperature, to temper, harden and cure the rubber.

A modified form of truss, illustrated in Figures 4 and 5, is shown to illustrate the adaptability of the sheath of the present invention for other types of trusses. This modified truss, generally referred to by the numeral 25, comprises a pair of truss pads 26 which may be joined by an adjusting strap 27 having a plurality of openings 28 therein. At its rear, each pad 26 is provided with a stud 29 for selective engagement in openings 28.

The truss further comprises a pair of springs 31, generally made of steel, the lower ends of the springs being each provided with an opening for alignment with a corresponding opening near the lower end of a bar 34, two such bars being provided, one for each of said springs. Each bar terminates at its other end in a hinge 33 having a central opening therein to receive by means of screws 37 or otherwise, the lower end of an adjusting bar 32, its upper end being provided with a horizontal slot 36 in which may be adjustably entered the stud 29 in pad 26. At their other ends, springs 31 may be joined by an adjusting strap 39 having a plurality of openings 40 for selective engagement with studs 41 as will hereinafter be described. When the openings at the ends of the springs are brought into alignment with corresponding openings in bars 34, each spring and bar is joined by means of rivet 35 or otherwise. All of the truss construction described is old and does not form a part of the present invention.

The present invention comprises a sheath for each spring, the sheaths being referred to by the numerals 30 and 30a respectively. The sheaths are identically like sheaths 15—15a and comprise each a central longitudinal tube to retain a spring, out outwardly tapered edges at each side of the tubular opening. One end of each sheath has a pad-like cap 38—38a superimposed thereon in the manner hereabove described, and each cap

may be provided with a stud 41 for selective engagement with openings 40 in adjusting belt 39.

Thus there have been shown two forms of trusses, each provided with sheaths of the present invention. By the use of the present sheaths, pressure of the springs is relieved. The tapered edge sections prevent discomfort in bending and sitting, and the caps are provided to relieve pressure at the free ends of the springs.

10 Thus there has been shown a sheath for the spring element of a truss in the preferred form of its embodiment, but it is to be understood that the disclosure is to be regarded as illustrative and descriptive only and not as restrictive or limitative to the exact details shown, applicant reserving the right to make such changes in the invention as may come within the scope of the appended claims without thereby departing from the spirit and the scope of the present invention.

15 Having thus described the invention, what is claimed as new and desired to secure by Letters Patent, is:

1. As an article of manufacture, a unitary sheath for the waist-embracing spring of a truss, 25 said sheath comprising a central tubular section in which the spring is adapted to be retained, and two edge sections one for each side of said tubular section and extending throughout the length of said tubular section, and a pad-like cap superimposed upon and closing one end of said sheath.

2. As an article of manufacture, a sheath for the waist-embracing spring of a truss, said sheath consisting of a unitary piece of material and comprising a central longitudinal tubular section in which a truss-spring is adapted to be housed, two outwardly tapered edge sections, one on each side of said tubular section, and a pad-like cap superimposed upon and closing one end of said 30 sheath.

3. A sheath for the waist-embracing spring of a truss, said sheath composed of a unitary piece of material and comprising a central longitudinal tubular section, two outwardly tapered edge sections, one on each side of said tubular section, a pad-like cap formed upon and closing one end of said sheath, and a stud in and extending outwardly from said cap.
